RESTRAINING GARMENT

Mildred Disher, Nappanee, Ind.

Application February 1, 1957, Serial No. 44,698

Term of patent 14 years

(Cl. D3—17)

I claim:

The ornamental design for a restraining garment, as shown.
